Des 816

Des. 816

Winslow Ames of Nashua, N. H.

Letters Patent No. 816, Dated July 13th 1856

The schedule referred to in these Letters Patent, and making part
of the same.

To all whom it may concern:

Be it known, that I, Winslow Ames of
the city of Nashua, County of Hillsborough, and State of New Hampshire,

142

Des. 816

have invented or produced a new and useful design for a Box Stove Plate, and I do hereby declare that the same is described and represented in the following specification and accompanying drawings, letters, figures, and references thereof.

Of the said drawings Fig. 1, shows a front view of the Plate, and Fig. 2, shows a vertical section of the same, on the red line A. B.

My design consists in the employment of the scrolls c, c, c, c, c, c, arranged in an arch-like form, and supported by the columns D, D, D, each of said columns, consisting of a base b, two semi-spheroidal ornaments c, c', (with the intervening ornaments f, f') a semi-hexagonal shaft d, and ornamental caps, e.

Within and beneath the scrolls c, c, c, c, c, c, are placed the fan-like ornaments f, f, and within and between the columns D, D, D, are placed the star-like ornaments G, G, the whole of which described ornaments, when combined and arranged as shown in the accompanying drawings, constitute my invention or production.

I claim the combination and arrangement of the ornamental figures and forms represented, in the accompanying drawings, forming together the ornamental design for a Box Stove Plate
